DUAL VALVE CONTROL FOR GAS BURNERS

Filed April 3, 1944

UNITED STATES PATENT OFFICE

2,373,189

DUAL VALVE CONTROL FOR GAS BURNERS

Gustav Klein, Elkins Park, Pa.

Application April 3, 1944, Serial No. 529,380

2 Claims.

(Cl. 161—9)

In gas burners such as those used in gas ranges, it is desirable to have a dual burner ring one producing a relatively small or simmering flame, and the other producing a relatively high flame, the burners being intended to be used separately or jointly, and for predetermined lengths of time, according to requirements.

It is also desirable automatically to control the operation of the burners so as to be able to select both the time and the amount of heat to be applied in a given cooking operation.

Controls for accomplishing the objects hereinabove set forth have heretofore been produced, but it is the object of the present invention to produce an improved and simplified form of control which will be effective for the purpose intended.

These and other objects are effected by the invention as will be apparent from the following description and claims taken in connection with the accompanying drawing forming a part of this application, in which:

Fig. 1 is a fragmentary top plan view of a dual-ring gas burner provided with a control embodying my invention, certain parts being omitted;

Fig. 2 is a fragmentary and diagrammatic section on line II—II of Fig. 1;

Fig. 3 is a view of the left-hand portion of Fig. 1, showing the apparatus adjusted for manual instead of automatic operation;

Fig. 4 is a fragmentary sectional view on line IV—IV of Fig. 2;

Fig. 5 is a section on line V—V of Fig. 1; and

Fig. 6 is a section on line VI—VI of Fig. 3.

Referring to the drawing and more particularly to Fig. 1, 10 designates a gas burner having concentric burner rings 12 and 14. For the purpose of this specification, the ring 12 will be assumed to be the high-flame burner and the ring 14 will be considered as the low flame or "simmer" burner. The gas burner 10 is connected by two conduits 16 and 18 leading to the burner rings 12 and 14, respectively, in the usual way. The conduits 16 and 18 are selectively controlled by a valve 20, which is only shown in elevation since it is now available on the market and well-known to the trade as a Harper valve. The function of this valve is to permit the gas to reach both of the burners 12 and 14 or selectively to shut the gas from one or the other or from both of said burners. The parts heretofore described form no part of the present invention.

According to the present invention, it is desired to provide means for automatically and selectively controlling the operation of the burner rings 12

and 14. To this end, the stem operating the valve 20 is extended in the form of a shaft 22, the entire valve being suitably secured to a framework 24 which may be part of the range structure or which may be a separate support secured to the range. An operating shaft 26 extends through a wall 28 of the framework 24 and carries an actuating knob 30. The stem shaft 26 extends through and is rotatable in a bushing or bearing 32 carried by and extending through the wall 28. On the inner side of the wall 28 (or right-hand side, as viewed in Fig. 1, and on the left-hand side, as viewed in Figs. 5 and 6), the shaft 26 loosely carries a bushing 34. The bushing 24 carries a clock spring 36, one end of which is anchored to the bushing 34 and the other end of which is anchored to the frame 24, as at 38. In order to cause the bushing 34 to rotate with the shaft 26 when such rotation is desired, the bushing 34 is provided with a notch 40 adapted to engage a pin on the shaft 26 so as to lock the bushing 34 to the shaft 26. Fixed to the end of the shaft 26, next to the pin 42, is a sleeve 44. The sleeve 44 has a slot 46 which engages a pin 48 on the stem 22 to integrate the stem 22 and shaft 26 for joint rotation as long as the pin 42 engages the slot 46. The shaft 26 is biased in a direction to cause the pin 42 to engage the slot 46 by a coil spring 50 bearing on the remote end of the sleeve 44, as shown in Figs. 1 and 2.

The clock spring 36 functions to turn the bushing 34, and hence the shaft 26 and stem 22, in a direction closing the valve 20. In other words, when the knob 30 is turned, say in counterclockwise direction, the valve 20 is partially or wholly opened and gas flows through the conduits 16 or 18, or both, into the burners 12 and 14, or either of them as the case may be. If the knob 30 is released and no provision is made to retain it in the position to which it has been moved, the energy stored in the spring 36 will cause the shaft 26 and the stem 22 to turn in clockwise direction to close the valve 20.

In order to provide means for retaining the stem 22 and shaft 26 against shutting the valve 20 except as desired, the bushing 34 carries a cam 52 having two engaging stops 54 and 56 which are angularly spaced apart a sufficient distance to permit operation in the manner hereinafter described. The cam 52 is also provided with a stop 58, which, when the cam rotates in clockwise direction, as shown in Fig. 2, will abut against a stop 60 to limit rotation of the shaft 26. Disposed above the cam 52 and pressed downwardly by its own weight or by a spring (not shown) is a lever

62 which is pivoted, at 64, to a lug 66 carried by the front wall 28 or forming part thereof. The lever 62 is provided with a pin 68 which is adapted to lie transversely of the cam 52, and to engage the stops 54 or 56 of the cam to prevent rotation of the cam under action of the spring 36. In other words, when the knob 30 is turned to full-open position in counterclockwise direction, the cam 52 will also revolve until both of the stops 54 and 56 of the cam are to the left of the pin 68, as viewed in Fig. 2. When the knob 30 is released, the energy stored in the spring 36 will turn the cam 52 in a clockwise direction until the stop 54 engages the pin 68. The parts will remain in this position until the lever 62 is raised sufficiently to permit the pin 68 to clear the stop 54. When this is done, the shaft 26 and the stem 22 will turn in clockwise or valve-closing direction. If the lever 62 is maintained in its raised position for a sufficient length of time, the shaft 26, cam 52 and stem 22 will turn in clockwise direction till the valve 20 is completely closed. If the lever 62 is only raised momentarily and dropped again so that the pin 68 clears only the stop 54 and then drops to ride on the cam surface 10, the pin 68 will engage the stop 56. This will permit the shaft 26 and valve stem 22 to turn sufficiently to close the main burner ring 12 while the simmer burner 14 continues to operate. When the lever 62 is again raised, the pin 68 clears the stop 56 and the shaft 26 and stem 22 will revolve until the valve 20 is completely shut to extinguish the main burner 12.

In order to provide for automatic control of the operation thus far described, I use a conventional clock mechanism 72, which is illustrated only diagrammatically since it may be of any conventional design. The clock mechanism includes a shaft 74 adapted to be actuated by conventional spring or electric power (not shown). The shaft 74 actuates a pair of gears 76 and 78, which, in turn, are in mesh with gears 80 and 82. The gear 80 is carried by a sleeve 84 and the gear 82 is carried by a shaft 86 which is freely rotatable within the sleeve 84. The sleeve 84 carries a cam 88 and the shaft 86 carries a cam 90, the cams 88 and 90 being adapted to act on a pin 92 carried by an extension of the lever 62, as shown in Fig. 4. The sleeve 84 and shaft 86 are provided with setting knobs 94 and 96. The setting knob 94 is provided with a pointer 98 which is adapted to coact with a dial 100, and the setting knob 96 is provided with a pointer 102 adapted to coact with a second dial 104 on the face of the clock mechanism.

Operation

If it is desired to use the burners 12 and 14 jointly for a period of fifteen minutes and the burner 14 alone for a total period of one hour, the knob 94 is turned until the pointer 98 thereof points to the numeral 1 on the dial 100 and the knob 96 is turned until the pointer 102 thereof points to the numeral 60 on the dial 100. The knob 30 is then turned counterclockwise until the cam stops 54 and 56 clear the pin 68. The valve 20 is now opened and gas flows to both of the burners 12 and 14. The tendency of the spring 34 to close the valve is counteracted by engagement of the stop 54 with the pin 68. Simultaneously the clock mechanism, whether it be of the spring or electric type, is set in motion. At the expiration of fifteen minutes, the sleeve 84 will have been turned, by the shaft 74 and gear 76, sufficiently to cause the cam 88 to engage

the pin 92 and raise the lever 62. This causes the pin 68 to rise with the pin 92 until, at the exact moment that the pin 92 is about to drop off the high point of the cam 88, the pin 68 has been raised sufficiently to clear the stop 54. The spring 36 now revolves the shaft 26 and the stem 22 in a valve-closing direction, but before the stem 22 has turned sufficiently completely to close the valve, the pin 92 has dropped off the cam 88 and the pin 68 has dropped down on the cam surface 10, where it is in a position to engage the stop 56 and arrest further movement of the cam 52, shaft 26 and stem 22. In this position of the cam 52, the gas is shut off from the burner 12, but the burner 14 remains supplied with gas. When the clock mechanism has measured an additional period of 45 minutes, the shaft 86 will have been turned by gearing 78 and 82 to cause the cam 90 to engage the pin 92 and again raise the lever 62. This again causes the pin 68 to clear the stop 56, thus permitting the cam 52, shaft 26 and stem 22 to be turned by the spring 36 until the stop 58 abuts against the stop 60. Before the stop 58 has reached the stop 60, the valve 20 will have been completely closed to shut the flow of gas from the main burner 12. While I have shown the dials 100 and 104 as providing for one hour and fractions thereof, it is obvious that the calibration may be varied according to requirements.

When it is desired to operate the burners independently of the automatic mechanism described, the shaft 26 is pushed inwardly, or to the left as viewed in Figs. 5 and 6, until the pin 42 clears the notch 40 and the knob is turned to cause the pin 42 to ride on the edge of the bushing 34, as shown in Fig. 6. This frees the bushing 34, cam 52 and spring 36 from the shaft 26, but the engagement of the pin 48 with the slot 46 in the sleeve 44, keeps the shaft 26 and the stem 22 integrated for joint rotation. In this position, the gas can be manually turned on, regulated or shut off.

What I claim is:

1. The combination with a gas burner having a main burner ring and an auxiliary burner ring, a pair of conduits for supplying fuel to said burner rings and a valve for shutting off the flow of fluid through one or both of said conduits and a valve stem for opening said valve, of means for automatically actuating said valve to shut the flow of fuel through one of said conduits upon the lapse of a predetermined relatively short period of time and to shut the flow of fuel through the other of said conduits upon the lapse of a relatively long period of time comprising, a main shaft operatively connected to said stem and rotatable in a valve-opening direction, a main cam carried by said shaft, a pair of angularly-spaced stops carried by said shaft, a coil spring adapted to be wound up to store energy when said shaft is turned in valve-opening direction, said spring biasing said shaft in valve-closing direction, an arm pivoted for rotation about a horizontal axis, a first pin carried by said arm and adapted to engage said stops, a time measuring device including a stub shaft, means for rotating said stub shaft, a sleeve coaxial with said stub shaft and means for rotating said stub shaft and said sleeve, a first cam carried by said shaft, a second carried by said sleeve, means for setting said cams so that the effective portions thereof will be angularly spaced, and a second pin carried by said arm transversely of and normally resting on the periphery of both of said first and second cams.

the angularly-spaced effective portions of said first and second cams being adapted successively to contact said second pin and raise said arm, successively to bring said first pin out of engagement with the stops on said main cam, upon the lapse of consecutive periods of time, whereby said spring will actuate said main shaft in valve-closing direction to shut the flow of fuel through one of said conduits upon the lapse of the short period of time and whereby said spring will rotate said 10

shaft in valve-closing direction to shut the flow of fuel from the other of said conduits upon the lapse of the long period of time.

2. The structure recited in claim 1 together with means for temporarily disengaging said main cam and said spring from said main shaft to permit manual opening and closing of said valve.

GUSTAV KLEIN.
